UNITED STATES PATENT OFFICE.

WILLIAM H. HAWS, OF JOHNSTOWN, PENNSYLVANIA.

METALLIC RAILWAY-TIE CONSTRUCTION.

1,151,463.

Specification of Letters Patent. Patented Aug. 24, 1915.

Application filed January 28, 1915. Serial No. 4,909.

To all whom it may concern:

Be it known that I, WILLIAM H. HAWS, a citizen of the United States, residing at Johnstown, in the county of Cambria and 5 State of Pennsylvania, have invented certain new and useful Improvements in Metallic Railway-Tie Construction, of which the following is a specification.

This invention has reference to metallic 10 railway tie construction, and has to do more particularly with means for securing the rails to the ties.

The objects of the invention are to provide means for securely holding the rails to 15 the ties against lateral movement; to permit accurate gaging of the tracks; to permit lateral adjustment of the rails to compensate for wear of the sides of the rail treads where engaged by the wheel flanges, 20 and to provide for the absolute locking of the rail holding structures even though the normal holding devices shall become loosened.

In accordance with the present invention 25 the tie may be in the form of a channel member, or in the form of an I-beam, or simply in the form of a flat plate, these three forms being taken as indicative of any suitable form of metallic tie, but usually the tie is 30 constructed of some form of structural steel requiring no treatment other than the punching of a few holes. In some forms of the invention one flange of the rail is held by a permanently fastened abutment clamp, 35 in which case the other flange of the rail is held by a clamp plate in embracing relation to the flange and to the under face of a web of the tie, which at the particular point is provided with a perforation traversed by a part 40 of the clamp plate. In conjunction with this clamp plate there is provided a wedge member capable of being driven through the perforation or perforations traversed by the clamp plate, so as to force the clamp plate 45 into firm clamping relation to the rail flange. The wedge is finally secured in place by a bolt or other fastening means and by making this wedge of malleable metal and with suitable wings it may be bent into locking 50 relation to the tie in a manner holding it absolutely in position, but at the same time permitting it to be bent back to its first form for withdrawal from the tie. Under some circumstances the permanently fixed

rail clamp is omitted and both flanges of the 55 rail are engaged by clamp plates both secured by appropriate wedges, and in some instances liners may be provided for the perforations through the tie.

With the present invention the rails are 60 fixedly secured in place on the ties without any liability of displacement, but are readily loosened from the ties and may be readily adjusted toward or from each other, and especially toward each other to take up 65 wear caused by the action of the wheel flanges upon the inner edges of the treads of the rails.

The invention will be best understood from a consideration of the following detailed description, taken in connection with the accompanying drawings forming a part 70 of this specification with the further understanding that while the drawings show a practical form of the invention, the latter is 75 not confined to any strict conformity with the showing of the drawings, but may be changed and modified so long as such changes and modifications mark no material departure from the salient features of the 80 invention.

In the drawings:—Figure 1 is a plan view of a portion of a tie with a rail secured thereto by the securing means of the present invention. Fig. 2 is a section on the line 85 2—2 of Fig. 1. Fig. 3 is a plan view similar to Fig. 1, but showing a somewhat different adaptation of the invention. Fig. 4 is a section on the line 4—4 of Fig. 3. Fig. 5 is a section similar to that of Fig. 2 illustrating 90 the use of a liner. Fig. 6 is a view similar to Fig. 4 and showing another use of a liner. Fig. 7 is a view similar to Fig. 1, but showing still another adaptation of the invention. Fig. 8 is a section on the line 8—8 of Fig. 95 7. Fig. 9 is a view similar to Fig. 3 and showing an adaptation of the securing means shown in Fig. 7. Fig. 10 is a section on the line 10—10 of Fig. 9. Fig. 11 is a section on the line 11—11 of Fig. 1. 100 Fig. 12 is a section similar to Fig. 6 but showing the use of the invention with a thin or plate tie. Fig. 13 is a section on the line 13—13 of Fig. 8. Fig. 14 is a perspective view of one end of a tie formed of channel steel. Fig. 15 is a perspective view of one of the wedge members. Fig. 16 is a perspective view of a clip which may be em- 105

ployed in connection with the wedge member of Fig. 15. Fig. 17 is a perspective view of another form of wedge member. Fig. 18 is a perspective view of a clip which may be used in conjunction with the structure of Fig. 17. Fig. 19 is a perspective view of a liner.

Referring to the drawings there is shown a tie 1 which in most of the forms illustrated is of the channel type of structural steel. As shown in Figs. 8, 9 and 13 the tie 1^a is of the I type of structural steel, while in Fig. 12 the tie is in the form of a flat plate 1^b. These three examples of different forms of ties are deemed to be sufficient to show that the present invention is not at all limited to any particular form of metal tie. In Figs. 1 to 12 there is also shown a track rail 2 which may be considered as of the ordinary type having the usual flanges 3, 4, these flanges being thus particularly referred to simply to facilitate the description to follow, and not as distinguishing the rail from any ordinary track rail. In the channel form of tie the connecting web between the marginal webs is designed to receive and support the rail. In the I form of tie one of the end webs constitutes the rail supporting portion of the tie, and in the flat or plate like tie 1^b the rail rests directly upon one flat face of the plate.

In Fig. 1 there is provided a clamp plate 5 secured to the rail receiving face of the tie by rivets 6, or in any other appropriate manner, and one edge 7 of the plate 5 is appropriately bent to overlie the corresponding flange of the rail, this flange in the particular form shown being the flange 4.

In the structure shown in Figs. 1 and 2 the rail receiving face of the tie 1 is pierced by laterally spaced passages 8 and extending through these passages are tongues 9 formed on one edge of a clamp plate 10 appropriately shaped to override and bear against the flange 3 of the rail 2. Each tongue 9 is bent upon itself so that its extremity points toward that edge of the plate 10 remote from that from which the tongues spring, and these tongues are located at the ends of the side of the plate from which they spring. The tongues 9 being bent upon themselves are also spaced from the corresponding face of the plate 10, so that when the tongues are introduced through the passages 8 the free ends of the tongues engage under the top web of the tie with the plate 10 bearing against the top of the rail flange 3.

In the structure of Fig. 1 and associated figures the tie is pierced for the passage of a bolt 11 and a corresponding bolt hole being indicated at 12 in Fig. 14. The bolt 11 is provided with a spacer nut 13 and a clamp nut 14 and between these two nuts is lodged a slotted arm 15 extending from a

wedge block 16. Extending from the sides of this block in opposite directions are other arms 17 terminating in wedge extensions 18 bent at approximately right angles to the arms 17 and to the plane of the block 16. These wedge extensions 18 taper lengthwise and are of a width and length to enter the respective perforations 8 in engagement with the tongues 9 of the clamp plate 10. In the structure of Figs. 1 and 2 the parts are so proportioned that when the wedges 18 are driven simultaneously into the passages 8 one edge of each wedge engages a tongue 9 and the other edge engages the corresponding side of the passage 8, so that the clamp plate 10 is driven by the wedge connection on to the flange 3 of the rail 2 and at the same time forces the flange 4 under the overhang 7 of the clamp plate 5. This most effectively clamps the rail flanges tightly against the top face of the tie. The clamp wedge block may be made of malleable steel or iron, the word steel being chosen to represent either iron or steel, and the bifurcated or slotted arm 15 has its slot represented at 15^a traversed by the bolt 11 with the nut 13 serving as a spacer and lock nut, and the nut 14 serving to clamp the arm 15 firmly against the nut 13. The wedge block serves to force the rail and clamp plates into firm union, and when this is accomplished and the track rails have been suitably gaged, the extremities of the wedge extensions 18 are bent toward or from each other, so as to fixedly lock the wedge block in its holding position against any possibility of loosening even though under the jar of traffic the nut 14 should become loosened. These wedge extensions are readily accessible in the several forms of tie shown in the drawings.

Instead of employing the permanently fixed clamp plate 5, two sets of clamp plates 10 and corresponding wedge blocks 16 may be employed, as shown in Figs. 3 and 4, where the same reference numerals are employed, since the parts are mere duplicates. In such instance, however, there is provided an additional set of perforations corresponding to the perforations 8, and designated 8^a in the drawings, and an additional bolt hole 12^a is also provided, as best shown in Fig. 14. With the structure shown in Figs. 3 and 4 it is advisable in the original installation to have the flange 4 of the rail, which flange is the one toward the opposite rail, with its edge about coincident with the corresponding margins of the perforations 8^a. The passages or perforations 8 and 8^a are made longer in the direction of the length of the tie than the width of the wedge extensions 18, so that when these wedge extensions are driven in to the full extent against the tongues 9 they do not fully fill the passages 8^a. Therefore there is intro-

duced into each passage 8^a a liner 19 shown separately in Fig. 19. This liner comprises a U-shaped strip of metal of suitable size having a yoke portion 20 adapted to abut 5 the corresponding edge of the passages 8 or 8^a with the legs of the U arranged above and below the web of the tie pierced by the passages 8 or 8^a. The liner forms an abutment for the corresponding edge of the wedge 10 18, so that under such circumstances the tongues 9 of the clamp plate 10 are forced against the other edge of the perforations 8 or 8^a as the case may be, and the rail is so located that the corresponding edge of the 15 web 4 is then about coincident with the edges of the passages 8^a, the structures of Figs. 3 and 4 being considered. The distance between the passages 8 and 8^a is less than the combined width of the flanges 3 and 4 of the 20 rail, so that the outer edge of the flange 3 now somewhat overrides the inner edges of the passages 8. The plates 10 applied to the flange 3 are engaged by the wedges 18 of the appropriate wedge block, which in this case 25 also bears against what constitutes the outer walls of the passages 8, these passages being those nearest to the corresponding end of the tie. In the course of traffic that edge of the rail tread engaged by the wheel 30 flanges becomes worn, and when this wearing reaches a certain degree, say, three-eighths of an inch more or less, it is necessary to compensate therefor. Under such circumstances the wedges 18 are removed and the 35 liners 19 are taken out of the passages 8^a and introduced into the passages 8, thus permitting a shift of the rail toward the other rail and thereby reducing the gage of the track. This permits the ready adjustment 40 of the rails to compensate for the increase in gage due to wear, so that the useful life of the rails is correspondingly increased and it is not until the rail has had a prolongation of life to practically double what it 45 otherwise would have that it is necessary to wholly discard the rail and replace it by a new one.

Under those circumstances in which the structure of Fig. 1 is employed, the wear of 50 the rails is taken up by initially forming the wing 7 to permit the adjustment of the rail toward the plate 5 for a limited distance, and under these circumstances the liner 19 is introduced into each perforation 55 8, and the wedges 18 are driven into position so as to force the flange 3 of the rail 2 tightly into the space beneath the wing 7 with the clamp plate 10 then having its tongues 9 in engagement with the corresponding walls of the passages 8. This arrangement is shown in Fig. 5 and illustrates the final adjustment of the rail after having its tread worn to the limit permitted before adjustment must take place.

60 In Fig. 6 the liner 19 is shown as located

in the outer passages 8, that is, those close to the end of the tie, instead of in the passages 8^a as in Fig. 4, and Fig. 6 represents the final compensating adjustment of the rail with the arrangement of Fig. 4.

70 In the structures so far described a single wedge block 16 is provided on one side or the other, or both sides of the rail to bring about the securing of the rail in place. Under some circumstances the wedge block 16 75 may be replaced by two wedges, such as illustrated in Figs. 7, 8, 9, 10 and 17, and in such instance a clamp plate shown in Fig. 18 is employed. The single wedge members are adapted each to a single hole or perforation 8 or 8^a and each comprises a plate 20^a 80 having one end formed with a longitudinally disposed entering slot 20^b and at the other end this plate is formed with two arms 21 in substantial parallelism and extending 85 from opposite sides of the corresponding end of the plate at approximately right angles thereto. These two arms are wedge shape and so may be termed wedges like the wedge extensions 18 of the wedge block 90 16. The slot 20^b is traversed by a bolt 11, as before, but there are two bolts 11 arranged side by side and spaced like the passages 8 and 8^a traversed by the wedges 21. These passages in Figs. 7, 8, 9, 10 and 13 95 extend through the upper webs of an I beam 1^a constituting the tie, and are arranged on opposite sides of the stem or center web of the I beam. In conjunction with the wedge plates 20^a are clamp plates 10^a, having 100 tongues 9^a like the tongues 9 of the plate 10, but inset a short distance from the ends of the plate, the passages 8 being correspondingly spaced. Otherwise the structures of Figs. 7 to 10 and 13 and 17 correspond with 105 the structures previously described with reference to other figures of the drawing. In Fig. 7 a clamp plate 5^a having a wing or tongue 7^a and held to the tie 1^a by rivets 6 is provided with the tongue 7^a of less width 110 than the top web of the tie, and substantially corresponding in width to the length of the plate 10^a. Two wedge devices 20^a are provided in the structure of Fig. 7, one for each 115 passage 8. In Fig. 9 a similar arrangement is provided, except that the plate 5^a is substituted by another pair of wedge devices 20^a entering passages 8^a like the structure of Fig. 3, and in the form of Fig. 9 liners 19 may be employed as before, and 120 for a similar purpose. In the structures of Figs. 7 to 10 the spacer nuts 13 are omitted, but nuts 14^a serve to clamp the wedge plates in position.

The structure of Fig. 12 is substantially 125 like Fig. 6, except that the parts are shown applied to a tie 1^b in the form of a flat plate instead of a webbed beam of structural steel, and so needs no special description.

In the initially installed position of the 130

parts the liners are placed in the perforations 8^a, these being the perforations farthest away from the ends of the tie, and, therefore, the presence of the liners determines the farthest distance apart of the rails. When the inner sides of the treads, that is, the sides of the treads of the rails toward each other, become worn to a sufficient extent the liners are removed from the inner perforations 8 and placed within the outer perforations 8, so that the rails are then brought together by a distance represented by the thickness of the yoke portions of the liners, the perforations 8 and 8^a being of sufficient width lengthwise of the ties to permit such adjustments. When this is done the facing edges of the treads of the rails of the track then becomes readjusted into the original gage and the rails wear until worn away to a corresponding extent, after which they must be discarded. Whether one wedge be used with the wedge elements spread apart, or two wedges be used each with the wedge elements close together, but the wedges themselves spread apart, the rail is engaged at points considerably separated although the separation is less than the width of the tie, and the rail is firmly held to the tie by the clamp plates having the tongues in embracing relation to the tie. While the wedges provide means whereby the clamp plates are forced into close and rigid connection with the flanges of the rail, the wedges cannot loosen so long as the bolts 11 or the nuts thereon hold. Loosening, however, may be effectively prevented by bending the extremities of the wedge extensions toward or from each other, as the case may be, somewhat after the manner of treating cotter pins, and no force to which these wedges are subjected in the ordinary course of traffic is sufficient to disturb them or to cause them to loosen to any material extent, so that the rails remain at all times in intimate contact with the ties and the road bed is therefore particularly firm and contributes to the ease of travel.

The various structures which are included in the present invention have the advantage of being producible out of sheet metal of suitable gage. For instance, the clamp plates 5 and 5^a are susceptible of manufacture from heavy sheet metal, the ends of the plate 5^a being turned about the flanges of the tie 1^a, as indicated at 5^b in Fig. 7. The clamp plates 10 and 10^a are both producible from sheet metal of suitable gage cut and bent into appropriate shape, and the wedge devices 16 and 20^a are also producible from sheet metal of suitable gage cut and bent into shape. Of course, these parts may be in the form of drop forging, and some of them might be in the form of castings, but in any event the wedge members should be of a malleable nature to permit the extremi-

ties of the wedge extensions or arms being bent into locking position with respect to the tie through which they extend.

What is claimed is:

1. In track construction, a metallic tie having a track supporting face with passages therethrough adjacent to the position to be occupied by the track rail and spaced apart transversely of the tie, a clamp plate having a portion adapted to overlie the flange of the rail and provided with tongues spaced apart in conformity with the spacing of and extending through said passages and engaging the under face of the tie supporting the rail, wedge members each having wedge extensions traversing the passages through the tie in engagement with the tongues of the clamp plate, and fastening means for the wedge members secured to the tie, said wedge members having the wedge extensions bendable in a direction to lock beneath the rail supporting portion of the tie. 70

2. In track construction, a metallic tie provided with means for engaging one side of the flange of a track rail and provided with passages through the track supporting face of the tie with the rail flange normally encroaching on the passages, a clamp plate having tongues extending through the passages in embracing relation to the rail flange and tie, and wedges extending through the passages in position to engage the tongues and provided with fastening means fast to the tie for holding the wedges in wedging relation to the said tongues. 90

3. In track construction, a metallic tie having passages through its track supporting surface and spaced apart laterally with respect to the length of the tie, holding means for one side of the rail in closer relation to the passages than the width of the base of the rail, a clamp plate having tongues adapted to traverse the passages with the clamp plate in engagement with the corresponding rail flange, and the tongues underriding the track supporting portion of the tie, a wedge plate provided with an edge portion adapted to traverse the passage through the tie in position to force the clamp plate in clamping engagement with the rail, and means for securing the wedge devices to the tie, said securing means being fast to and carried by the tie. 105

4. In track construction, a metallic tie having passages therethrough spaced apart laterally of the length of the tie, track holding devices in position on the tie with relation to the rail to hold the latter with the base or flange portion in partial overriding relation to the passages, a clamp plate having tongues thereon spaced apart to traverse the passages and shaped to engage under the track receiving portion of the tie, the wedge means having as many wedge por- 120
125
130

tions as there are passages through the tie adjacent to a track rail, and means for securing the wedge means to the tie.

5. In track construction, a metallic tie having passages therethrough spaced apart laterally of the length of the tie, track holding devices in position on the tie with relation to the rail to hold the latter with the base or flange portion in partial overriding relation to the passages, a clamp plate having tongues thereon spaced apart to traverse the passages and shaped to engage under the track receiving portion of the tie, wedge means having as many wedge portions as there are passages through the tie adjacent to a track rail, and means for securing the wedge means to the tie, said wedge means having wedge extensions of malleable metal and of a length to extend through the perforated portion of the tie and to be bent in locking relation to the tie.

6. In track construction, a metallic tie having passages therethrough spaced apart laterally of the length of the tie, track holding devices in position on the tie with relation to the rail to hold the latter with the base or flange portion in partial overriding relation to the passages, a clamp plate having tongues thereon spaced apart to traverse the passages and shaped to engage under the track receiving portion of the tie, wedge means having as many wedge portions as there are passages through the tie adjacent to a track rail, and means for securing the wedge means to the tie, said wedge means having wedge extensions of malleable metal and of a length to extend through the perforated portion of the tie and to be bent in locking relation to the tie, the track holding devices also including liners adapted to the perforations, and the perforations being of a length in the direction of the length of the tie to receive the clamp plate tongues, the wedges and the liners.

45 7. In track construction, a metallic tie having passages therethrough adjacent to the track receiving portion of the tie, a clamp plate having tongues adapted to traverse the passages with the clamp plate engaging a base flange of the rail, wedges adapted to traverse the passages and engage the tongues of the clamp plate, fastening means for the wedges, and liners independent of the fastening means and adapted to be lodged in the passages between the wedges and those ends of the passages remote from the clamp plates.

8. In track construction, a metallic tie having passages therethrough spaced apart laterally of the length of the tie in position to be normally overridden by the base flange of the track rail in the initial position thereof at the end of the passages toward the center of the tie, a clamp plate adapted

to engage over the corresponding flange of the rail and provided with tongues extending through the passages into underriding relation to the portion of the tie supporting the rail, and wedge devices spaced apart laterally of the length of the rail and entering the correspondingly spaced passages to engage the tongues of the clamp plates and force the latter into clamping relation to the rails.

9. In track construction, a metallic tie having means for engaging the tie and also the base portion of the rail on opposite sides of the latter, said rail engaging means having associated therewith removable interchangeable means interposable between the tie and rail engaging means and providing a range of adjustment lengthwise of the tie to permit movement of the rails toward each other to compensate for wear of the inner edges of the treads of the rails by the car wheels.

10. In track construction, a metallic tie having a fixed clamp plate for engaging the flange of a track rail on the side thereof toward the center of the track and said tie having passages therein adjacent to the position occupied by the outer edge of the flange of the rail and spaced apart crosswise of the tie, a clamp plate having tongues spaced apart corresponding to the spacing of the passages through the tie and adapted to be passed through the passages into underriding relation to the tie where supporting the track, and wedge means having wedge portions spaced apart corresponding to the spacing of the passages and adapted to enter the latter to force the clamp plates into clamping relation to the track rails.

11. In track construction a metallic tie provided with means for holding one side of the track rail and provided near the other side thereof with passages spaced apart in the direction of the width of the tie, a clamp plate having tongues thereon adapted to traverse the passages and engage under the track supporting portion of the tie, and a wedge member having spaced wedges thereon adapted to traverse the spaced passages and provided with means for securing the wedge member to the tie.

12. In track construction a tie having means thereon for engaging one side of a track rail and provided with passages therethrough adjacent to the other side of an installed track rail, a clamp plate having return tongues thereon adapted to traverse the passages with the tongues underriding the corresponding portion of the tie, and the plate engaging over the corresponding portion of the flange of the rail, and wedge members each provided with a pair of wedge extensions adapted to traverse the passages to force the clamp plate into en-

gaging relation with the rail and provided with means for holding the wedge member to the tie.

13. In track construction, a tie having 5 pairs of passages therethrough on opposite sides of the position to be occupied by the track rail and the passages of each pair being spaced apart laterally of the tie, clamp plates having tongue extensions adapted to 10 traverse the passages into underriding relation to the corresponding portion of the tie with the plate overriding the corresponding flange of the track rail, wedge members for each pair of passages having wedge extensions traversing the passages in position to 15 force the clamp members into engagement with the track rail, and means for securing the wedges to the tie.

14. In track construction, a tie having 20 pairs of passages therethrough on opposite sides of the position to be occupied by the track rail and the passages of each pair being spaced apart laterally of the tie, clamp

plates having tongue extensions adapted to 25 traverse the passages into underriding relation to the corresponding portion of the tie with the plate overriding the corresponding flange of the track rail, wedge members for each pair of passages having wedge extensions 30 traversing the passages in position to force the clamp members into engagement with the track rail, and means for securing the wedges to the tie, the pairs of passages 35 being spaced apart a distance less than the width of the base of the rail, and liners for one pair of passages and adapted to be removed therefrom and installed in the other pair of passages to provide for shifting the rails lengthwise of the tie to compensate for 40 wear.

In testimony whereof I have affixed my signature in presence of two witnesses.

WILLIAM H. HAWS.
